DA-576

Ex

OF D 15,990

Design No. 15,990

March 24, 1885.

DESIGN FOR A CURTAIN FABRIC.

UNITED STATES PATENT OFFICE.

JOHN HARTLEY, OF PHILADELPHIA, PENNSYLVANIA, ASSIGNOR TO BARNES & BEYER, OF SAME PLACE.

DESIGN FOR A CURTAIN FABRIC.

SPECIFICATION forming part of Design No. 15,990, dated March 24, 1885.

Application filed February 19, 1885. Term of patent 3½ years

To all whom it may concern:

Be it known that I, JOHN HARTLEY, a subject of the Queen of Great Britain, residing at Philadelphia, in the county of Philadelphia and State of Pennsylvania, have invented and produced a new and original Design for a Curtain Fabric; and I do hereby declare that the photographic print accompanying this specification conveys to any one skilled in the art 10 a clear understanding of the same, and is sufficient to enable such person to use my invention.

The leading features of my design consist, first, in the representation at B of the arrangement of flowers, leaves, and branches,

the most prominent being the representation of four lilies in full bloom; second, in the representation at A and C of the ornamental borders, showing scrolls, flowers, leaves and branches, guards, and cross strips. These 20 parts, combined with B, represent the ornamental design of a dado for a curtain fabric.

I claim as my invention and desire to secure by Letters Patent—

The design for a curtain fabric, as shown 25 and described.

JOHN HARTLEY.

Witnesses:

JOHN SHINN,
P. McCAFFRAY.
